UNITED STATES PATENT OFFICE.

FRANK R. BATCHELDER, OF WORCESTER, MASSACHUSETTS.

WOVEN CARRIER.

1,211,276.

Specification of Letters Patent.

Patented Jan. 2, 1917.

Application filed June 3, 1916. Serial No. 101,639.

To all whom it may concern:

Be it known that I, FRANK R. BATCHELDER, a citizen of the United States, residing at Worcester, in the county of Worcester, 5 State of Massachusetts, have invented a certain new and useful Improvement in Woven Carriers, of which the following is a specification, reference being had therein to the accompanying drawings.

10 The present invention is a division of that forming the subject of my application for United States patent for improvements in woven carriers, filed May 23, 1916, Serial No. 99,322.

15 It has relation to pocketed carriers made of woven material, namely carriers on the order of those which are used for holding and carrying cartridges, packaged first-aid supplies, etc.

20 Among the pocketed carriers to which the invention is applicable are comprised cartridge carriers, hospital corps belts, medical officers' belts, and others having various special adaptations.

25 More particularly, the invention relates to the covers which are provided in connection with the pockets of carriers of the said general class.

Carriers of the general class in question, 30 made of flexible woven material and known sometimes as woven carriers, have been provided heretofore with cover-flaps made of flexible woven material. Almost invariably, however, the ordinary pocket cover or flap 35 has been a mere strip of web, pointed, equipped with a fastener, and arranged to be drawn from back to front over the mouth or opening of the pocket. This form of cover has not constituted a complete closure

40 for the opening of the pocket, but on the contrary has left it possible for water to enter between the cover and the lateral edges of the pocket; also for dust to penetrate easily into the pocket while troops are 45 on the march; and also for cartridges or similar small objects to become lost from the pocket, particularly with mounted troops on the trot, or when the wearer of the carrier is lying down.

50 None of the flaps or covers of woven material employed up to the present time meets satisfactorily the purposes of my broad or generic invention presented in the parent application aforesaid, in respect of being 55 capable of affording complete protection to the contents of a pocket as well as safe-

guarding effectually against accidental escape of such contents, and in other respects. So far as I am aware, it never has been perceived heretofore how to make out of woven 60 material an effective and practical cover which will thus meet the said purposes. Woven fabric is not as well adapted as leather to be made up and used in cut, shaped, and stitched form, and accordingly 65 only simple forms of cover-flaps such as referred to above have been employed in connection with the carriers aforesaid. Notwithstanding that these simple forms of cover-flaps afford only incomplete or inadequate protection, nothing better has entered 70 into use. On the other hand, woven material has been found better than leather in different practical respects for use in the case of pocketed carriers, for instance as regards durability and capacity to withstand 75 climatic conditions, and by reason of its greater flexibility. It can be produced of greater strength with less weight, and of greater uniformity in strength and other 80 desirable qualities. It therefore is used in the manufacture of pocketed carriers, notwithstanding the drawbacks and disadvantages which restrict its capabilities and prevent it from being shaped by cutting, and 85 the parts or pieces from being applied, united, and combined in the same manner in which leather might be. The comparative flexibility of woven material is at one 90 and the same time both an advantage and a disadvantage or drawback, the disadvantage or drawback residing in the fact that woven pockets do not have the requisite stiffness to enable them to retain definite 95 shapes accurately. Another disadvantage or drawback is that the cut edges of woven material are objectionable. They fray and present projecting and loose ends of threads, unless they are bound with tape or webbing or turned or folded in. When cut margins 100 are united by stitches, the seams do not hold reliably unless the material is turned or folded over upon itself, in which case the bulkiness of the two or more thicknesses 105 comprised in a folded-over portion frequently is objectionable and undesirable.

The invention has for its general object the production of a practical improved flexible cover which shall afford complete protection for the contents of the pocket with 110 which it is combined, by effectually excluding moisture, mud, sand and dust; which

shall effectually insure against the escape of articles (as, for instance, cartridges in the case of a cartridge carrier) and which shall be of a construction enabling the drawbacks or disadvantages of woven material, above referred to, to be avoided or properly taken care of.

The invention provides a woven carrier comprising a body-web and a woven pocket projecting from the face of the said web, with a cover comprising a hood of flexible material, flexibly united with the back of the pocket, having a front which extends down in front of the front wall of the said pocket, and having side-skirts which extend down alongside the sides of the pocket, and prevent the existence of openings at the opposite sides of the closed and covered pocket. The top of the hood-like cover embodying the invention has a well-defined rectangularity and an area corresponding with the cross-section of the filled pocket, and the side-skirts form well-defined angles with the said top.

The present invention consists, more specifically, in a hood-like cover comprising a strip of flexible material which is secured by its rear end at the back of the pocket, its intermediate portion constituting the top of the said cover, and its forward portion constituting one thickness of the front of the cover, and a transverse strip having an intermediate portion constituting a second thickness of the cover front, and end-portions which constitute side-wings or skirts of the cover.

A pocket cover made in conformity with the invention constitutes a complete covering and protection against the entrance of water, dust, etc., and against the escape of small objects contained in the pocket. It is especially serviceable and useful in the case of belts carrying hospital corps supplies, these supplies frequently including packets of gauze thinly wrapped in muslin or paper, and similar first-aid and medical packages. It is useful also where troops are required to carry paper boxes or cartons containing clips as packed at the cartridge-making factory. For instance, it is desired in some countries to issue to troops sealed cartons which are not to be opened except when firing orders are given. The cartons are of light paper and if exposed to the weather speedily become softened or weakened and broken. By means of a pocket cover made according to my invention, effective protection is afforded in these different cases.

In the drawings,—Figure 1 is a front view of a short section of a hospital corps belt, showing one of the pockets thereof as when filled with packages, and having the hood-like cover thereof closed down in place and fastened. Fig. 2 is a view of the same from the left-hand side in Fig. 1. Fig. 3 is a top

view thereof. Fig. 4 is a front view and Fig. 5 a side view, showing the cover raised. Fig. 6 is a front view showing a modified embodiment of the present invention, the lower portions of the pocket and the body- web being broken away.

The body or band-portion of a belt or carrier is marked 1 in each of the different views in which it appears, and the pocket is marked 2. As shown, the said body or band-portion and pocket are formed of flexible woven material, and are produced integral with each other by proper procedure in weaving. Only one pocket is shown in each instance, and when desired a carrier 75 may consist of or be provided with but a single pocket, although usually in practice a carrier is furnished with a plurality of pockets. The invention is applicable in either case. The pocket is represented in 80 the different views, by way of illustration, as filled and expanded by packages 3, 3, such as commonly contain the supplies that are furnished to the hospital corps. The 85 filled pocket in these instances is substantially rectangular in cross-section. 90

In the case of each embodiment shown herein the cover is secured in place in proper relations with the pocket by means of a rearward extension 4 from the top of the 95 cover. This extension is made fast in some approved manner at the back of the pocket. Preferably it is inserted into a housing slit provided in the upper portion of web 1, as shown in the drawings, in which slit it is secured in practice by means of stitches or other convenient fastenings. The said housing slit is of the character of the housing slits shown, described and claimed in U. S. Letters Patent No. 1,139,629, granted 100 to me under date of May 18, 1915. Its 105 employment is preferred but is not indispensable.

The cover is composed of two strips of woven material fastened together in the required relations. One of such strips extends from front to rear and forms the extension 4, the top 5 of the cover, and one of the thicknesses of the front 6 of the cover. The other strip extends transversely and forms the two side-portions, wings, or skirts 7, 7, of the cover and one, 7^a, Fig. 4, of the thicknesses of the cover-front. The two thicknesses composing the cover-front are fastened together in this instance by lines 110 of stitches 19, 19, and 19^a, 19^a, Fig. 1. Lines 19, 19, are close to and parallel with the side-edges of the strip that extends from front to rear, such strip being a little wider than the filled pocket 115 is from side to side. The lines 19^a, 19^a, of stitches are close to and parallel with the top and bottom edges of the transverse strip. Other lines of stitches may be applied, and other or additional means for se- 120 125 130

curing the two strips together may be employed. The end-portions of the transverse strip are bent at right angles at the opposite sides of the other strip to produce the side-wings or skirts 7, 7. The top-edges of the wings or skirts are united to the side-edges of the cover-top by lines of stitches 70, 70, Figs. 2 and 5, or other connecting means. The free end of the strip extending from front to rear is folded back upon itself and stitched to produce the pointed end of the cover-front, and the free ends of the side-wing portions of the transverse strip are folded back upon themselves, or hemmed, as shown at 71, to hide and protect cut or raw edges at the back edges of the wings or skirts and to give smooth and firm edges that will not fray or ravel.

The top 5 of the cover made as just explained has a well-defined rectangularity closely corresponding in area and general proportions with the horizontal cross-section of the filled and expanded pocket. The side-wings or skirts and front form well-defined angles with the said top, and the side-wings or skirts form well-defined angles with the front. Thus the cover has and retains a shape corresponding with that of the filled and expanded pocket. When it is closed down into place as in Figs. 1, 2 and 3 it constitutes a complete protecting hood for the pocket. As will be seen in the said views, the skirts or side-wings 7, 7, close in the spaces at opposite sides of the top of the pocket so that there are no openings such as exist at those places when the old style cover-flaps are employed. The entrance of rain, snow, sand, mud, or other matter at such places is prevented, and small articles contained within a pocket cannot escape.

Fastening means is provided in practice for the purpose of holding the cover or hood securely closed. The drawings show means of usual character comprising a stud 11 applied to and projecting from the front wall of the pocket, and a coöperating socket 12 applied to the front of the cover or hood.

Preferably, though not necessarily in all cases, strips of webbing woven of the proper width, with firm woven selvages, are employed in the construction of the cover or hood, thereby rendering unnecessary any folding or hemming of the longitudinal edges of such strips and avoiding bulkiness of the securing seams. In such case, the

side-edges of the cover-top and both the top and the bottom edges of the side-wings or skirts are selvage edges.

In the embodiment shown in Fig. 6, the construction resembles that shown in Figs. 1 to 5, except that at the outset the transverse strip is considerably longer than that of the latter views, and in making the cover such strip has its end-portions doubled back upon the intermediate portion thereof so as to produce wings or skirts 7^a, 7^a, which are of two thicknesses. The extremities of the said doubled-back end-portions are inserted between the intermediate portion of such strip and the forward end-portion of the other strip, and thus are concealed within the thickness of the cover-front. The two thicknesses of the transverse strip are held together along their lower edges by stitches. The back edges 7^b, 7^b, of the wings or skirts are constituted by the folds of the transverse strip.

What is claimed as the invention is,

1. A woven carrier having a pocket, and a hood - like cover therefor comprising a strip of flexible material which is secured by its rear end at the back of the pocket, its intermediate portion constituting the cover-top and its forward portion constituting one thickness of the cover-front, and a transverse strip having an intermediate portion constituting a second thickness of the cover - front and end - portions constituting side-wings or skirts of the cover. 90

2. A woven carrier having a pocket, and a hood-like cover therefor comprising a selvaged woven strip which is secured by its rear end at the back of the pocket, its intermediate portion constituting the top of the cover and its forward portion constituting one thickness of the front of the cover, and a transverse selvaged woven strip having an intermediate portion constituting a second thickness of the cover-front and end-portions which constitute side-wings or skirts of the cover, the two thicknesses of the cover-front fastened together and the top-edges of the side-wings or skirts fastened to the side-edges of the cover-top. 105

In testimony whereof I affix my signature in presence of two witnesses.

FRANK R. BATCHELDER.
